UNITED STATES PATENT OFFICE.

JAMES M. FLESHMAN, OF CORYDON, INDIANA.

FILE-HANDLE.

1,220,406.

Specification of Letters Patent.

Patented Mar. 27, 1917.

Application filed April 21, 1916. Serial No. 92,748.

To all whom it may concern:

Be it known that I, JAMES M. FLESHMAN, a citizen of the United States, residing at Corydon, in the county of Harrison, State 5 of Indiana, have invented certain new and useful Improvements in File-Handles; and I do hereby declare the following to be a full, clear, and exact description of the invention, such as will enable others skilled 10 in the art to which it appertains to make and use the same.

This invention relates to file handles, and has for its primary object to provide simple and efficient means for holding the file during the reciprocation incident to the operation of the latter without danger of injury to the hands of the operator, and without danger of the file becoming detached from the handle during the filing operation.

20 A further object of the invention is to provide a file handle of the character described and for the purposes set forth, which is capable of attachment to files of various sizes without making adjustments in the 25 handle.

A still further and particular object of the invention is to provide a handle of the type referred to which is of extremely simple and inexpensive construction, to which files may 30 be readily attached to or detached, which will prove practically everlasting in use, and which will prove thoroughly efficient in practice.

With these objects in view, together with others which will appear as the description proceeds, the invention resides in the novel combination and arrangement of parts, all as will be described more fully hereinafter, illustrated in the drawings and particularly 40 pointed out in the claim.

The invention will be best understood by reference to the accompanying drawings, wherein:

Figure 1, is a side elevation of a conventional form of file and illustrating the application of a handle embodying my invention,

Fig. 2, is a bottom plan view of the device illustrated in Fig. 1, and

50 Fig. 3, is a detail perspective view of the file attaching plate removed from the handle.

Referring now more particularly to the drawings, 4 indicates a hand grip, the same 55 being similar in size, material and construc-

tion as the ordinary wood saw handle, an opening 5 being provided therein through which the fingers may project to firmly grip the handle.

The lowermost edge of the handle 4 is 60 straight, and secured to this edge by suitable rivets or screws 6 is a thin metallic plate 7. This plate is of a length and width equal to that of the lower edge of the handle 4. The lowermost face of the plate 7 is 65 flat as shown and is formed adjacent one end with a pair of spaced outwardly projecting bosses 8. These bosses extend inwardly from the rear end of the plate, and have their adjacent faces disposed perpendicular 70 to the lower face of the plate 7. These bosses are so formed upon the plate as to be spaced from each other at their forward ends a distance slightly greater than the distance between the adjacent faces at their 75 rearward end, the said faces thus converging from the forward toward the rearward end of the plate and are straight. These bosses project downwardly from the under face of the plate 7 a distance substantially equal 80 to or slightly less than the thickness of the ordinary flat file, and the converging sides of the ordinary handle portion 9 of a file are adapted to be engaged between the converging walls of the bosses 8 to firmly bind the 85 said tapered handle between the said bosses. It is thus apparent that the file will be firmly secured to the handle, and in such manner that slight tapping of the protruding end of the file handle will loosen the 90 file so that the same may be readily withdrawn from binding engagement between the bosses 8. It will be observed further that the bosses are so constructed and arranged as to enable the same to engage with 95 file handles of various widths. By forming the bosses 8 so as to project from the plate 7 a distance equal to or less than the thickness of the ordinary file, it is apparent that the device may be used as a metal plane on a 100 flat surface, the entire abrading surface of the file being enabled to contact with the flat surface operated upon.

What is claimed is:

A file holder comprising a plate having 105 a flat upper face and a lower face provided at its rear end with a pair of bosses having opposed faces at right angles to the plane of the remainder of the lower face and converging rearwardly, the remainder of said 110

lower face forming a continuous unbroken plane, said plate being provided with screw receiving openings, a handle seated on the upper face of the plate, and screws passing through the openings and into the handle, 5 the heads of said screws lying wholly within said plate.

In testimony whereof, I affix my signature, in the presence of two witnesses.

JAMES M. FLESHMAN.
